(57)

CLAIM

The ornamental design for a bucket, as shown and described.

DESCRIPTION

1. Bucket

1.1 : Perspective

1.2 : Perspective

1.3 : Left

1.4 : Right

1.5 : Front

1.6 : Back

1.7 : Top

The broken lines immediately adjacent to the shaded area define the bounds of the claimed design and form no part thereof; the broken lines showing the remainder of the article represent unclaimed subject matter and form no part of the claimed design.

1 Claim, 7 Drawing Sheets
